ARCHIBALD G. SHAVER, OF CHICAGO, ILLINOIS, AND BENJAMIN W. MEISEL, OF CRESTWOOD, NEW YORK, ASSIGNORS TO THE REGAN SAFETY DEVICES COMPANY, INC., OF NEW YORK, N. Y., A CORPORATION OF NEW YORK

TRAIN CONTROL SYSTEM

Application filed October 1, 1926, Serial No. 138,869. Renewed June 14, 1932.

This invention relates to a train control system, and more particularly to an induction type of train control system; and has special reference to the provision of an improved induction train control system of the manual-automatic type.

A principal object of the present invention comprehends the provision of an induction train control system embodying automatic means operated in accordance with roadside conditions for producing a tripping operation of the vehicle carried apparatus to bring the vehicle to a halt combined with manually operable means for setting said vehicle carried apparatus to permit the same to move under a restricted speed.

A further prime desideratum of the present invention resides in the provision of vehicle carried apparatus for an induction system in which manual means are provided adapted to be operated by the engineman for resetting the vehicle carried apparatus to its normal unrestricted running condition provided the vehicle or train is running at or below a safe or restricted speed.

A still further prime object of the invention comprehends the provision of a manual-automatic train control system of the nature referred to in which the manually operated restoring or resetting mechanism is adapted to be controlled by the cooperative efforts of the engineman and fireman acting simultaneously providing a maximum degree of safety in restoring the tripped vehicle carried apparatus to its normal running condition when the roadside conditions have cleared.

A still further prime object of the invention centers about the provision of an induction train control system in which cab or vehicle signalling means are provided combined with the means for controlling the movement of the train, the construction and operation being such that the engineman as well as the fireman may be apprised of the roadside conditions so as to permit manual restoration under "safe" conditions; and the further provision of a system of this nature in which the manual restoration of the train control apparatus may be produced without

affecting the automatic control from the roadside of the vehicle or cab signalling means; and the still further provision of a system of this character in which the cab signalling means may be operated automatically to a restored state by cooperate vehicle and roadside inductor mechanism.

Still further objects of the invention include the provision of inductive roadside apparatus which may be operated to produce tripping and resetting operations of the vehicle carried apparatus with the use of comparatively few inductors both on the roadside and on the vehicle cooperating in a way to reflex energy from the vehicle through the roadside and back to the vehicle to produce the restoring or resetting operations; and the still further provision of an improved roadside inductive apparatus combined with detecting circuits which are operated to indicate the displacement of the roadside inductors or the breaking of any of the roadside inductor circuits.

To the accomplishment of the foregoing and such other objects as will hereinafter appear, our invention consists in the elements and their relation one to the other as herein-after more particularly described and sought to be defined in the claims, reference being had to the accompanying drawings which show the preferred embodiment of our invention, and in which:

Fig. 1 is a wiring diagrammatic view of the vehicle carried apparatus embodying the principles of the present invention, and

Fig. 2 is a wiring diagrammatic view of the cooperating roadside apparatus.

Referring now more in detail to the drawings and referring first to Fig. 1 thereof, there is provided a valve V for controlling the movement of the train by governing the operation of the air brake system, the said valve having a construction of the type disclosed in the patent to Allen B. Kendall No. 1,540,017 of June 2, 1925, the said valve being operated by an electromagnet device M, the actuation of which is controlled by the vehicle carried circuits about to be described.

The circuit normally governing the electromagnet M to permit unrestricted operation

of the train as in response to "clear" roadside conditions is energized from a source of energy E which comprises a potentiometer across the mains of the direct current generator G and the said circuit is controlled by direct current relay R2, the operation of which is in turn controlled by the manual and automatic controlling means to be described hereinafter. This control circuit for the electromagnet M comprises energy E, conductors 21 and 37, the coil 36 of the magnet M, conductor 35, a contact 34 of a manually operable push button device P1, conductors 33 and 80, contact 81 of a push button device P3, conductor 32, contact 31 controlled by the relay R2 and conductors 30, 29, 9, 10 and 11 back to the source of energy E. The contacts of the push button devices P1 and P3 are normally closed and are provided for a purpose to be explained hereinafter, and the contact 31 is closed normally when the relay R2 is energized. The source of energy E is connected to the generator G by means of the conductors 78 and 79 and is provided so that a 32-volt headlight generator circuit may be employed for the other apparatus to be described, while about 10 to 12 volts may be tapped for the operation of the direct current controlling elements.

The control relay R2 is governed by the operation of an inductor controlled circuit operated in accordance with roadside conditions to which a vehicle carried tripping inductor TI is responsive, and under normal running conditions this inductor controlled circuit is normally closed and is controlled by a contact 28 of the control relay R2 and a second contact 2 governed by a trip relay T-TR having the armature T and the field TR, the said trip relay being the one that is controlled by the trip inductor TI. The said circuit for the control relay R2 comprises energy E, conductor 1, trip relay contact 2, conductor 3, a switch 23, conductors 19 and 24, the coil of relay R2, conductors 26 and 27, stick contact 28 of relay R2, and conductors 29, 9, 10 and 11. It will be seen that with this circuit the opening of the trip contact 2 will open the circuit at both the trip contact and the stick contact 28 so that the circuit will persist in open condition even though the trip relay contact 2 is again closed.

The trip relay T-TR is an alternating current relay, the field TR of which is always energized from an A. C. source comprising a "converter" connected as shown to the D. C. generator G, the field TR being connected to the converter leads by means of conductors 74, 62, 61, 66, 65 and 73.

The tripping inductor TI comprises inductively coupled coils *a* and *b*, the coil *a* being an energizing coil and the coil *b* being an energy receiving coil, the former being connected to the A. C. source by means of the conductors 63 and 64 and the latter coil

b being connected by means of the conductors 69 and 70 to the armature T of the trip relay. This tripping inductor embodies preferably a construction similar to that described and claimed in the patent to A. G. Shaver No. 1,521,332 of Dec. 30, 1924, and in the copending application of A. G. Shaver Ser. No. 506,595 filed Oct. 10, 1921.

Normally the armature T of the trip relay is energized through the transformer inductor TI to maintain the vehicle carried circuits described in normal condition. When, however, the said tripping inductor TI moves over the roadside inductor to be described under a "caution" or "danger" condition, the flux conditions between the coils *a* and *b* of the trip inductor TI are disturbed sufficiently to effectively deenergize the trip relay to open the contact 2 and thus to deenergize the circuit controlling the operating device or magnet M which effects an application of the brakes. Movement of the trip inductor TI, however, over the roadside inductor means under "clear" conditions is unaccompanied by any substantial change in the flux conditions of the trip inductor so that the vehicle carried apparatus is undisturbed and is maintained in normal running condition.

In the system of the present invention, there are provided cab or vehicle signalling means also controlled from the roadside to apprise the engineman of the roadside conditions in a manner to permit him to manually control the movement of the vehicle under "safe" operating conditions for setting the vehicle carried apparatus to move under a speed restriction or for restoring the same under given conditions to move without a speed restriction. This cab signalling means comprises the "clear" indicating light L1 and the "danger" indicating light L2 controlled by a second control relay R1 which is also connected to the inductor controlled circuit to be governed thereby. Normally the relay R1 is energized through a circuit comprising energy E, conductor 1 of the inductor controlled circuit, trip contact 2, conductor 3, switch 23, conductors 19 and 4, relay R1, conductors 5 and 20, stick contact 7 of the relay R1 and conductors 8 to 11. It will be seen from this construction that when the inductor controlled circuit is tripped, the relay R1 will be deenergized along with the relay R2. The deenergization of the relay R1 extinguishes the signal L1 and energizes the signal L2, the same being accomplished by the operation of a contact 16 controlled by the relay R1, the said contact normally making at its front point a circuit comprising energy E, conductors 21, 49 and 17, signal L1, conductor 45, contact 16, conductor 15 and conductors 8 to 11. When relay R1 is deenergized, the contact 16 drops to its back point and the circuit is completed

through the shunt path which includes the conductor 18 and signal L2.

In accordance with the principles of the present invention the cab signalling means is controlled only from the roadside and the operation of the same cannot be modified by any of the vehicle carried manual restoring means, except that relay R1 will be deenergized and stop signal L2 consequently displayed when the switch 23 is operated to close on conductor 25, as may be the case in releasing when the vehicle has stopped with its inductors TI and RI over the track inductors 114 and 112 or has passed into a stop block. To accomplish this the relay R1 is governed by automatic inductive reset mechanism. The reset inductive mechanism on the vehicle comprises a reset inductor RI connected by means of conductors 71 and 72 to an armature R of an alternating current relay the field of which is the field TR of the trip relay; and this reset armature controls a pair of contacts 13 and 59, the former of which serves for resetting or restoring the 25 operation of the signal control relay R1. Preferably the reset inductor is provided with a compensating circuit having a coil 77 connected to a condenser c by means of conductors 75 and 76. When the reset inductor RI receives an energizing impulse the reset relay contacts 13 and 59 are closed, the closing of the former causing the relay R1 to be reenergized by means of the circuit comprising conductor 1, trip contact 2 (closed as will be seen hereinafter when a resetting impulse is received), conductor 3, switch 23, conductors 19 and 4, the relay R1, conductors 5 and 14, the closed contact 13 and conductors 12 and 11. The resetting 30 impulse is obtained only when the vehicle inductors move over the roadside inductors but the closing of the circuit described, in closing the contact 7 of relay R1, closes the holding circuit previously described for the relay R1 so that the said relay remains in restored condition although the contact 13 opens after the vehicle inductor passes the roadside inductor.

After the train control relay R2 is tripped 50 to bring the vehicle to a halt, the operated device or electromagnet M may be manually restored by the mechanism now to be described to permit the vehicle to proceed at or below a restricted speed, this when the cab signalling means indicates that the roadside conditions remain at "caution" or "danger". This manual restoring and modifying mechanism comprises a circuit for operating a relay R3 and for placing the 55 same under the control of a speed controller SC, the circuit being operated by the push button P1. The relay R3 when deenergized under "danger" conditions may be energized provided the speed of the train does not 60 exceed a predetermined limit, by means of

the push button P1, the circuit for energizing the relay R3 comprising energy E, conductor 1, trip contact 2, conductors 3 and 22, relay R3, conductor 48, contact 47, conductor 46, contact 40 (closed when P1 is operated), conductor 39, contacts of speed controller SC closed when the restricted speed is not exceeded, and conductors 38, 10 and 11.

The push button P1 after being operated must be released so as to prevent a mis-operation thereof, and this is enforced by the provision of the contact 34 which is provided, as previously described, in the circuit to the magnet M, the opening of which contact deenergizes the magnet M. The magnet M is made sufficiently slow-acting so that the same does not become effectively deenergized by the proper operation of the push button P1. The stem connected to the contact 40 is separate from the lower stem portion of the push button P1 so that the contact 40 may be held closed by the relay R3 if the speed under "danger" conditions is not exceeded, the closing of this contact maintaining the circuit described closed to keep the relay R3 energized.

With this recited construction it will be seen that under "danger" conditions if the restricted speed is not exceeded, the relay R3 may be energized and held energized; and this is provided for energizing the valve magnet M through a circuit comprising conductors 21 and 37, magnet coil 36, conductor 35, contact 34, conductors 33 and 52, contact 51 closed, conductors 50 and 39, contacts of speed controller SC, and conductors 38, 10 and 11. When the speed of the vehicle exceeds the restricted speed the stick circuit to the relay R3 is opened and maintained open so that the last-described circuit to the magnet M is opened to bring the vehicle to a halt. This, however, may be again modified by operation of the push button P1 when the vehicle is reduced to or below the speed limit.

It is desirable to apprise the engineman of the time when the push button P1 may be operated, and this is effected by the provision of a signal 42 associated with the relay R3, which signal is operated when the vehicle circuits are tripped and the speed of the vehicle is reduced to the desired limit. The circuit controlling the signal 42 comprises conductor 1, trip contact 2, conductors 3 and 22, conductor 43, signal 42, conductor 41, contact 40 closed on its back point, conductor 39, speed controller SC, and conductors 38, 10 and 11.

It will be noted that the circuit governing the relay R3 is taken through the trip contact 2 so that this circuit may be deenergized regardless of speed conditions when a trip operation of the circuits is produced. It will also be seen that a single trip contact 2 operates all of the relays to control the tripping condition thereof.

It will be further noted that there is an energizing circuit for relay R3 under normal clear conditions when relay R2 is energized provided R3 has been previously energized. This normal circuit governing relay R3 comprises: energy E, conductor 1, contact 2 of trip relay T, conductors 3, and 22, relay R3, conductor 48, contact 47 of push button P2, conductor 46, contact 40 of relay R3 closed, conductor 50, contact 51 of relay R3 closed, conductors 52 and 80, contact 81 of push button P3, conductor 32, contact 31 of relay R2, conductors 30 and 29, 9, 10 and 11. The object of this circuit for relay R3 controlled by relay R2 is to provide a means for maintaining relay R3 energized and thus operate the apparatus under more favorable conditions and avoid unnecessary wear and vibration which is naturally associated with deenergized parts. More important, however, is the fact that with R2 energized, as in a clear block, the engineman may push the button P1, energizing R3 preparatory to the speed being reduced to the prescribed rate, thus only making it necessary for him to operate switch 23 to close on conductor 25 when passing under the prescribed speed rate into a restrictive or stop block, as will be herein-after described. Relay R3, however, cannot be restored to the energized position through the automatic restoring means as described for relays R1 and R2. The only way this relay R3 can be restored to the energized position is by means of the push button P1, and providing also the electrical circuits for this relay are otherwise complete. When relay R3 is energized, the circuit to signal 42 is open because contact 40 of relay R3 is closed in its up position. Under this condition when the train is operating in a clear block but approaching a more restrictive block, the engineman may desire to use signal 42 as a fixed speed indicator before arriving at the restrictive block; if so, he may push the button P2 so as to deenergize relay R3 which will then close contact 40 of this relay to conductor 41, thus closing the open circuit to signal 42, which signal will be displayed if the engineman has reduced the speed of the train to or below the restricted rate. If the signal is not displayed, the engineman will know that the speed must be further reduced if he desires to avoid a brake application on entering the restrictive block.

A desideratum of the present invention comprehends the provision of a train control system in which the inductor controlled circuits or the relay governing the "clear" operation of the train may be manually restored under "safe" running conditions of the vehicle to permit unrestricted running thereof. To accomplish this, the inductor controlled circuit for the relay R2 is made restorable to its normal condition by the cooperative efforts of the engineman and fireman, who in

concert may restore the apparatus if the vehicle is moving at or below the restricted speed, the engineman being apprised of the roadside conditions by observing the operation of the cab signalling means L1 and L2. To these ends there are provided two release buttons ERB and FRB to be operated one by the engineman and the other by the fireman for restoring the train control relay R2 without, however, restoring the signal relay R1. The restoring circuit for the relay R2 comprises conductor 1, trip relay contact 2, conductor 3, switch 23, conductors 19 and 24, relay R2, conductors 26 and 57, contact 56 of FRB closed by the fireman by operating push button P3, conductor 55, contact 54 of ERB closed by the engineman by operating push button P2, conductor 53, contact 51 making on its back point, conductors 50 and 39, speed controller SC and conductors 38, 10 and 11.

The contact 51 should be on its back point, and if perchance the relay R3 is energized when this operation is desired, the same is re-energized by the opening of the contact 47 of the release button ERB, which contact is in the circuit controlling the relay R3. To prevent the fireman's button from being held in a misoperated position, the contact 81 thereof is provided, which contact is in the normal or clear circuit of the electromagnet device M; therefore, if the fireman's button P3 is held or stuck in the reverse position, then restricted speed is the best that can be had, and if, at the same time, the button P1 is held or stuck in the reverse position, then the train will be stopped.

With this construction it will therefore be seen that if the speed of the vehicle is at or below the restricted speed, the relay R2 may be reset by the cooperative action of the engineman and fireman; and this is effected without modifying the operation of the signal control relay R1.

For the purpose of operating the train circuits to permit the vehicle or train to move at a speed restriction when a train is stopped with the vehicle trip inductor over the roadside trip inductor (which would release the trip contact 2) there is provided the switch 23 heretofore referred to, which switch may be moved from the position shown to connect with the conductor 25, and when this is done the relay R3 will be energized by the following circuit: conductors 21, 49 and 25, switch 23, conductor 22, relay R3, conductor 48, contact 47, conductor 46, contact 40 closed by P1, conductor 39, speed controller SC, and conductors 38, 10 and 11. After the train passes the roadside trip inductor, the switch 23 must be moved to its full-line position, otherwise the train cannot proceed except at the restricted speed governed by the controller SC.

Switch 23 also serves another purpose 130

which is, that with R3 energized and the speed of the vehicle under the prescribed rate, this switch 23 may be held closed during the interval of the vehicle passing over the roadside inductors into a restrictive or stop block.

As the vehicle passes into a stop block, the trip contact 2 is opened, and in such a case switch 23 being closed on conductor 25, a bypass circuit is provided to keep R3 energized.

10 If the engineman and fireman fail to manually reset or restore the inductor controlled circuit operating the relay R2, provision is made for effecting the automatic restoration thereof, this being accomplished by the second contact 59 of the resetting relay R, which contact controls the restoring circuit to the relay R2 as follows: conductor 1, trip contact 2, conductor 3, switch 23, conductors 19 and 24, relay R2, conductor 26, conductor 58 (in dotted lines) the contact 59, and conductors 60, 12 and 11.

It will be noted that the inductors and the trip and reset relays thereof are all controlled by alternating current energy while the remaining vehicle carried apparatus is controlled and operated by direct current energy, this producing a very desirable train control arrangement. Preferably the power factor compensator PFC is connected across the A. C. source by the conductors 67 and 68 to render operation of the A. C. circuits more efficient.

Referring now to Fig. 2 of the drawings, there is shown a section of railway track 35 divided into blocks or sections X, Y and Z insulated from each other as at W, W, three full blocks or sections being shown with signal equipment for each of the blocks and with roadside inductive mechanism shown to be operated by the signalling equipment. The blocks indicate the condition of "danger" for the section Z, the condition of "caution" for the section Y and the condition of "clear" for the section X due to the presence of the vehicle in the block next succeeding the block Z.

The roadside inductive apparatus for cooperating with both the trip and reset vehicle inductors comprises for each block a pair of inductors 112 and 114 connected in a circuit which comprises the inductor 112, conductor 111, condenser 110, a contact 109 controlled by a relay H, conductor 118, a signal circuit breaker SCB having a contact 117 movable to the position shown, conductor 115, inductor 114 and conductor 113. This circuit is closed both under "clear" and "caution" conditions as shown in the blocks X and Y and is open for the "danger" condition as shown for block Z, the said signal circuit breaker being operated by the movement of the semaphore signal. The inductors 112 and 114 comprise a combined trip and reset device generally designated as T and R, the inductor 114 being adapted for cooperation with the vehicle tripping inductor TI and the induct-

70 tor 112 being adapted to cooperate with the vehicle resetting inductor RI, as shown in Fig. 1 of the drawings.

The cooperation between the vehicle carried and roadside inductors is more fully described in the copending application of F. M. Rosenzweig Ser. No. 636,553, filed May 4, 1923, where such construction is broadly claimed, and it will suffice here to say that when the roadside circuit described is closed, the vehicle carried apparatus moves over the roadside apparatus without altering the vehicle carried circuits, whereas when the roadside circuit is open the inductor 114 will be an inert state and will disturb the flux conditions between the coils of the tripping inductor TI to trip the vehicle carried circuits, and further that after such a tripping operation is produced, the closing of the roadside circuit will effect the resetting operation of the vehicle carried circuits by energy transmitted from the vehicle inductor A to the roadside inductor 114 and reflexed back to the vehicle by means of the inductors 112 and RI.

90 In the preferred embodiment of the invention there is provided associated with the combined trip and reset inductors T and R a second trip inductor T_P also controlled from the semaphore through a signal circuit breaker SCB having the contact 107 by means of the circuit comprising the inductor T_P, conductor 102, condenser 103, contact 104, conductor 105, contact 107, and conductor 108. The tripping inductor T_P is preferably arranged at braking distance A from the entrance to the next block, while the combined trip and reset inductor system T and R is arranged preferably at engine and tender length B from the terminal of the block, as indicated by the arrowed lines in Fig. 2 of the drawings. With this construction a tripping operation may be produced at braking distance, so that if the conditions ahead are cleared before the vehicle being operated reaches the associated combined trip and reset devices, a clearing operation will be produced to permit further unimpeded movement of the train, thereby permitting speed-up movements under "clear" conditions. If, however, the roadside conditions persist at "danger", another tripping operation will be produced at the trip and reset inductors T and R even though the vehicle carried apparatus may be manually restored.

110 It is highly desirable to provide means for detecting the integrity of the roadside inductive mechanism so that when such mechanism is accidentally displaced the defect will be reflected in roadside apparatus of another block to indicate the unsafe condition to a passing vehicle. To accomplish these ends there are provided circuit breaking controllers operated by displacement of the inductors as well as means for controlling the 115 120 125 130

condition of operation of inductors in succeeding blocks when the inductor circuit of a preceding block is broken. The controllers for breaking the inductor circuits when the inductors are displaced are represented by the crosses in the roadside circuits described, the said crosses indicating the presence of apparatus of the type described and claimed in the patent to Joseph Beaumont No. 1,586,772 of June 1, 1926. The breaking of the inductor circuits controls inductors of other blocks by the detecting circuits shown in phantom or dotted lines in Fig. 2 of the drawings which will now be described.

The relays H heretofore referred to control contacts 104 and 109 of the inductor circuits so that when these contacts are open the inductor circuits will be in a condition to trip the vehicle mechanism, and each of the relays H for a given block is controlled by the detecting circuits provided for the inductors of the next succeeding block. The relay H of the block Y, for example, is controlled by the circuit starting with battery 125, common wire 170, conductor 171, contact 172 controlled by the track relay T. B., conductor 173, relay H, conductor 120, conductor 102, detector controller X, inductor T_P in block Z, conductor 108, conductor 121, a contact 122 controlled by detecting relay DR, conductors 123 and 124 back to the battery 125. When the contact 122 of relay DR, or detector controller X or the inductor circuit are opened the relay H for block Z will be deenergized to produce the tripping operations in the inductors of block Y.

The controlling detecting relay DR is in a circuit embracing the combined trip and reset inductor T and R in block Z, which circuit comprises the battery 125, conductor 124, relay DR, conductor 126, conductor 115, inductors 114 and 112 in block Z and conductors 111 and 127. Therefore when these inductors in block Z are displaced to break the inductor circuit or the inductor circuits are broken, the detecting relay DR is deenergized to produce the tripping operations in the inductors of the block in the rear, Y. It will be noted that the detecting circuit is operative regardless of the opening of the trip and reset circuit at the contact of the signal circuit breaker SCB, so that the detecting circuits are always in effect.

While the detecting circuits associated with the detecting relay DR and its contact 122 have been shown connected to the tripping and resetting inductor combinations of the block Z, the same being shown tied in with the relay H of the block in the rear, it will be understood that similar circuits are provided for each of the other blocks, and the same manner of tying the same in with a control relay of a block preceding is carried out. To avoid unnecessary duplication and confusion these other circuits

have been omitted from Fig. 2 of the drawings. As showing, however, another method of accomplishing similar results, we show a different set of detector circuits for block Y and the manner in which the same are connected to the relay H of block X.

In this alternative method the inductors T_P and T and R are provided with a detecting circuit which may be traced from the relay H of the block X as follows: The lower pole 130 of the source of energy 131 connected to common line 170, conductor 174, contact 175 controlled by the track battery T. B. connected to the block Y, conductor 176, the relay H of block X, conductor 132 connected to conductor 102 above the condenser 103, trip element T_P, conductors 108, 133 and 115, the elements of the inductors T and R, conductor 111 and conductor 134. It will be noted that this circuit is tied into the circuit of T_P in shunt with the condenser 103 therein and is similarly tied into the circuit of the inductor T and R in shunt with the condenser 110 therein.

It will therefore be noted that for both systems of circuits illustrated in alternative arrangement in Fig. 2 of the drawings, there is provided an A. C. circuit (including a condenser) for each of the inductor circuits, this A. C. circuit cooperating with the A. C. vehicle carried apparatus shown in Fig. 1 of the drawings. It will be further noted that the detector circuits while they partially include the inductor elements and parts of the circuits thereof, are D. C. circuits. These D. C. circuits are circuits of high impedance to the A. C. currents and do not affect the operation of the inductors to influence the vehicle carried apparatus, but are merely affected by the condition of the inductor circuits. It will also be seen that the detector circuits are effective whether or not the inductor circuits are open or closed at the control point represented by the control element SCB.

The relay H for each of the blocks X, Y and Z is desirably the relay governing the operation of the semaphore signalling apparatus, this being provided so that the de-energization of a relay such as H of block Z when the circuit to the trip and reset combination T and R in block Z is broken by displacement of the inductors will be reflected in the semaphore signal of block Z as well as in the trip and reset combination in block Y.

The use and operation of the manual-automatic induction system of the present invention will in the main be fully apparent from the above detailed description thereof. It will be further apparent that while we have shown and described our invention in the preferred form, that many changes and modifications may be made in the structure disclosed without departing from the spirit of

the invention, defined in the following claims.

We claim:

1. In an induction train control system, vehicle carried apparatus comprising a device for controlling the movement of the train, vehicle signalling means, an inductor controlled circuit operable when tripped by cooperating roadside apparatus for operating the said device to stop the train and for simultaneously operating said vehicle signalling means to indicate therein the corresponding roadside condition, a second inductor controlled circuit for resetting the vehicle signalling means, manual means for modifying the stop operation of said device and for placing the same under the control of the speed of the train to permit the train to move under a speed restriction, and manually operable mechanism effective only when the train is not exceeding a restricted speed for resetting said inductor controlled circuit to reset the said device to its normal unrestricted operation without resetting the vehicle signalling means.

2. In an induction train control system, vehicle carried apparatus comprising a device for controlling the movement of the train, vehicle signalling means, an inductor controlled circuit operable when tripped by cooperating roadside apparatus for operating the said device to stop the train and for simultaneously operating said vehicle signalling means to indicate therein the corresponding roadside condition, a second inductor controlled circuit for resetting the vehicle signalling means, means operable manually by the engineman for modifying the stop operation of said device and for placing the same under the control of the speed of the train to permit the train to move under a speed restriction, and manually operable mechanism operable combinedly by the engineman and fireman for resetting said inductor controlled circuit to reset the said device to its normal unrestricted operation without resetting the vehicle signalling means.

3. In an induction train control system, vehicle carried apparatus comprising a device for controlling the movement of the train, vehicle signalling means, an inductor controlled circuit operable when tripped by cooperating roadside apparatus for operating the said device to stop the train and for operating said vehicle signalling means to indicate therein the corresponding roadside condition, a second inductor controlled circuit for resetting the vehicle signalling means, means operable manually by the engineman for modifying the stop operation of said device and for placing the same under the control of the speed of the train to permit the train to move under a speed restriction, and manually operable mechanism operable combinedly by the engineman and fireman for

resetting said inductor controlled circuit to reset the said device to its normal unrestricted operation.

4. In an induction train control system, vehicle carried apparatus comprising a device for controlling the movement of the train, vehicle signalling means, an inductor controlled circuit operable when tripped by cooperating roadside apparatus for operating the said device to stop the train and for simultaneously operating said vehicle signalling means to indicate therein the corresponding roadside condition, a second inductor controlled circuit for automatically resetting the vehicle signalling means and the said device, and manually operable mechanism for resetting said inductor controlled circuit to reset the said device to its normal unrestricted operation without resetting the said signalling means.

5. In an induction train control system, vehicle carried apparatus comprising a device for controlling the movement of the train, vehicle signalling means, an inductor controlled circuit operable when tripped by cooperating roadside apparatus for simultaneously operating the said device to stop the train and for operating said vehicle signalling means to indicate therein the corresponding roadside condition, a second inductor controlled circuit for automatically resetting the vehicle signalling means, and manually operable mechanism effective only when the train is not exceeding a restricted speed for resetting said inductor controlled circuit to reset the said device to its normal unrestricted operation without resetting the said signalling means.

6. In an induction train control system, vehicle carried apparatus comprising a relay for controlling the movement of the train, a second relay for controlling the operation of cab signalling means, an inductor controlled circuit connected to both of said relays and operable when tripped by cooperating roadside apparatus for operating both relays to effect the stopping of the train and the simultaneous operation of the vehicle signalling means to indicate the corresponding roadside condition, a second inductor controlled circuit for resetting the signal relay, and manually operable mechanism for resetting the inductor controlled circuit for the train control relay without affecting the operation of said signal relay.

7. In an induction train control system, vehicle carried apparatus comprising a relay for controlling the movement of the train, a second relay for controlling the operation of cab signalling means, an inductor controlled circuit connected to both of said relays, a trip relay for said circuit operable when tripped by cooperating roadside apparatus for operating said circuits and relays to effect the stopping of the train and the

simultaneous operation of the vehicle signalling means to indicate the corresponding roadside condition, a second inductor controlled circuit for resetting the signal relay, a manually operable mechanism for resetting the inductor controlled circuit for the train control relay without affecting the operation of said signal relay, an A. C. source of energy for said trip relay and a D. C. source of energy for said other relays and circuit.

8. In an induction train control system, vehicle carried apparatus comprising a relay for controlling the movement of the train, a second relay for controlling the operation of cab signalling means, an inductor controlled circuit connected to both of said relays and operable when tripped by cooperating roadside apparatus for operating both relays to effect the stopping of the train and the simultaneous operation of the vehicle signalling means to indicate the corresponding roadside condition, a second inductor controlled circuit for resetting the signal relay and the train control relay, and manually operable mechanism for resetting the inductor controlled circuit for the train control relay without affecting the operation of said signal relay.

9. In an induction train control system, vehicle carried apparatus comprising a relay for controlling the movement of the train, a second relay for controlling the operation of cab signalling means, an inductor controlled circuit connected to both of said relays and operable when tripped by cooperating roadside apparatus for operating both relays to effect the stopping of the train and the simultaneous operation of the vehicle signalling means to indicate the corresponding roadside condition, a second inductor controlled circuit for resetting the signal relay, and mechanism manually operable by the combined action of the engineman and fireman provided the train is not exceeding a restricted speed for resetting the inductor controlled circuit for the train control relay without affecting the operation of said signal relay.

10. In an induction train control system, vehicle carried apparatus comprising a relay for controlling the movement of the train, a second relay for controlling the operation of cab signalling means, an inductor controlled circuit connected to both of said relays controlled by contacts of said relays, an inductor relay controlling another contact of said circuit and operable when tripped by cooperating roadside apparatus for operating both relays to effect the stopping of the train and the simultaneous operation of the vehicle signalling means to indicate the corresponding roadside condition, a second inductor controlled circuit for resetting the signal relay, and manually operable mechanism for resetting the inductor controlled circuit for the

train control relay without affecting the operation of said signal relay.

11. In an induction train control system, vehicle carried apparatus comprising a device for controlling the movement of the train, an inductor controlled circuit operable when tripped by cooperating roadside apparatus for operating said device to stop the train, manual means for modifying the stop operation of said device and for placing the same under the control of the speed of the train to permit the train to move under a speed restriction, manually operable mechanism effective only when the train is not exceeding said restricted speed for resetting said inductor controlled circuit to reset the said device to its normal unrestricted operation, and inductive means for automatically resetting said inductor controlled circuit.

12. In an induction train control system, vehicle carried apparatus comprising a device for controlling the movement of the train, an inductor controlled circuit operable when tripped by cooperating roadside apparatus for operating said device to stop the train, means manually operable by the engineman for modifying the stop operation of said device and for placing the same under the control of the speed of the train to permit the train to move under a speed restriction, mechanism manually operable by the engineman and the fireman cooperating together and effective only when the train is not exceeding said restricted speed for resetting said inductor controlled circuit to reset the said device to its normal unrestricted operation, and inductive means for automatically resetting said inductor controlled circuit.

13. In an induction train control system, vehicle carried apparatus comprising a device for controlling the movement of the train, an inductor controlled circuit operable when tripped by cooperating roadside apparatus for operating said device to stop the train, mechanism manually operable by the engineman and fireman acting together for resetting said inductor controlled circuit to reset the said device to its normal operation, and inductive means for automatically resetting said inductor controlled circuit.

14. In an induction train control system, vehicle carried apparatus comprising a device for controlling the movement of the train, an inductor controlled stick circuit operable when tripped by cooperating roadside apparatus for operating said device for producing a persisting train control operation thereof, mechanism embodying a circuit open at two spaced points and adapted to be closed by the cooperative efforts of the engineman and fireman and effective only when the train is not exceeding a restricted speed for resetting said inductor controlled circuit to reset the said device to its normal opera-

tion, and inductive means for automatically resetting said inductor controlled circuit.

15. In an induction train control system, vehicle carried apparatus comprising a device for controlling the movement of the train, a control relay for controlling the operation of said device, an alternating current inductor circuit for said control relay operable when tripped by cooperating roadside apparatus for tripping the said control relay to produce a train controlling operation in said device, a second control relay for placing said device under the control of the speed of the train to permit the train to move under a speed restriction, manually operable means for setting the said second control relay, manually operable mechanism effective only when the train is not exceeding the said restricted speed for resetting said first-mentioned control relay to reset the said device to its normal unrestricted operation, an alternating current source of energy for said inductor circuit and a direct current source of energy for said device and relays.

25. 16. In an induction train control system, vehicle carried apparatus comprising a device for controlling the movement of the train, a control relay for controlling the operation of said device, an alternating current inductor circuit for said control relay operable when tripped by cooperating roadside apparatus for tripping the said control relay to produce a train controlling operation in said device, a second control relay for placing said device under the control of the speed of the train to permit the train to move under a speed restriction, manually operable means for setting the said second control relay, manually operable mechanism for resetting said first-mentioned control relay to reset the said device to its normal unrestricted operation, an alternating current source of energy for said inductor circuit and a direct current source of energy for said device and relays.

45. 17. In an induction train control system, vehicle carried apparatus comprising a device for controlling the movement of the train, a control relay for controlling the operation of said device, an alternating current inductor circuit operable when tripped by cooperating roadside apparatus for tripping the said control relay to produce a train controlling operation in said device, a second control relay for placing said device under the control of the speed of the train to permit the train to move under a speed restriction, means operable by the engineman for setting the said second control relay, mechanism operable by the engineman and fireman acting together and effective only when the train is not exceeding the said restricted speed for resetting said first-mentioned control relay to reset the said device to its normal unrestricted operation, an alternating current source of energy for said inductor circuit and a direct

current source of energy for said device and relays.

18. In an induction train control system, vehicle carried apparatus comprising a device for controlling the movement of the train, a control relay for controlling the operation of said device, an alternating current inductor circuit for said control relay operable when tripped by cooperating roadside apparatus for tripping the said control relay to produce a train controlling operation in said device, a second control relay for placing said device under the control of the speed of the train to permit the train to move under a speed restriction, manually operable means for setting the said second control relay, manually operable mechanism effective only when the train is not exceeding the said restricted speed for resetting said first-mentioned control relay to reset the said device to its normal unrestricted operation, means for tripping the said second control relay when the said inductor controlled circuit is tripped, an alternating current source of energy for said inductor circuit and a direct current source of energy for said device and relays.

20. 19. In an induction train control system, vehicle carried apparatus comprising a device for controlling the movement of the train, a control relay for controlling the operation of said device, a trip relay for the control relay, an inductor circuit operable when tripped by cooperating roadside apparatus for tripping the said trip and control relays to produce a train controlling operation in said device, a second control relay for placing said device under the control of the speed of the train to permit the train to move under a speed restriction, manually operable means for setting the said second control relay, manually operable mechanism for resetting said first-mentioned control relay to reset the said device to its normal unrestricted operation, an alternating current source of energy for the inductor circuit and trip relay and a direct current source of energy for said device and control relays.

45. 20. In an induction train control system, vehicle carried apparatus comprising a device for controlling the movement of the train, a control relay for controlling the operation of said device, a trip relay for the control relay, an inductor circuit operable when tripped by cooperating roadside apparatus for tripping the said trip and control relays to produce a train controlling operation in said device, a second control relay for placing said device under the control of the speed of the train to permit the train to move under a speed restriction, manually operable means for setting the said second control relay, manually operable mechanism effective only when the train is not exceeding the said restricted speed for resetting said first-mentioned control relay to reset the said de-

vice to its normal unrestricted operation, an alternating current source of energy for the inductor circuit and trip relay and a direct current source of energy for said device and control relays.

21. In an induction train control system, vehicle carried apparatus comprising a device for controlling the movement of the train, vehicle signalling means, a control relay for said device, a control relay for said signalling means, an inductor controlled circuit operable when tripped by cooperating roadside apparatus for tripping both of said control relays, a third relay for placing said device under the control of the speed of the train to permit the train to move under a speed restriction, manually operable means for setting the said third control relay, manually operable mechanism for resetting the first-mentioned relay to reset the device to its normal unrestricted operation, and means connecting the inductor controlled circuit with said third relay whereby the said third relay is tripped when the inductor controlled circuit is tripped.

22. In an induction train control system, vehicle carried apparatus comprising a device for controlling the movement of the train, vehicle signalling means, a control relay for said device, a control relay for said signalling means, an inductor controlled circuit operable when tripped by cooperating roadside apparatus for tripping both of said control relays, a third relay for placing said device under the control of the speed of the train to permit the train to move under a speed restriction, manually operable means for setting the said third control relay, manually operable mechanism effective only when the train is not exceeding a restricted speed for resetting the first-mentioned relay to reset the device to its normal unrestricted operation, and means connecting the inductor controlled circuit with said third relay whereby the said third relay is tripped when the inductor controlled circuit is tripped.

23. In an induction train control system, vehicle carried apparatus comprising a device for controlling the movement of the train, vehicle signalling means, a control relay for said device, a control relay for said signalling means, an inductor controlled circuit operable when tripped by cooperating roadside apparatus for tripping both of said control relays, a third relay for placing said device under the control of the speed of the train to permit the train to move under a speed restriction, manually operable means for setting the said third control relay, mechanism manually operable by the engineman and fireman acting in cooperation and effective only when the train is not exceeding a restricted speed for resetting the first-mentioned relay to reset the device to its normal unrestricted operation, and means connecting the inductor

controlled circuit with said third relay whereby the said third relay is tripped when the inductor controlled circuit is tripped.

24. In an induction train control system, vehicle carried apparatus comprising a device for controlling the movement of the train, vehicle signalling means, a control relay for said device, a control relay for said signalling means, an inductor controlled circuit operable when tripped by cooperating roadside apparatus for tripping both of said control relays, a third relay for placing said device under the control of the speed of the train to permit the train to move under a speed restriction, manually operable means for setting the said third control relay and for placing the same under the control of the speed of the train, manually operable mechanism effective only when the train is not exceeding a restricted speed for resetting the first-mentioned relay to reset the device to its normal unrestricted operation, and means connecting the inductor controlled circuit with said third relay whereby the said third relay is tripped when the inductor controlled circuit is tripped.

25. In combination, vehicle carried mechanism, a vehicle carried energizing inductor associated with and adapted to be influenced for tripping the said vehicle carried mechanism, a vehicle carried A. C. source of energy therefor, a second vehicle carried inductor defining an energy receiving inductor associated with and adapted to be influenced for resetting the vehicle carried mechanism, and a roadside inductor means comprising a pair only of inductors connected in circuit, one of the inductors cooperating with the vehicle carried energizing inductor and the other of the inductors cooperating with the second vehicle carried inductor, the said pair of inductors being operable on open circuit for producing the tripping action and being operable when in closed circuit for producing the resetting action.

26. In combination, vehicle carried mechanism, a vehicle carried inductor including coupled energizing and energy receiving coils associated with and adapted to be influenced for tripping the said vehicle carried mechanism, a vehicle carried A. C. source of energy therefor, a second vehicle carried inductor associated with and adapted to be influenced for resetting the vehicle carried mechanism, and a roadside inductor means comprising a pair only of inductors connected in circuit, one of the inductors cooperating with the vehicle carried energizing coil and the other of the inductors cooperating with the second vehicle carried inductor, the said pair of inductors being operable on open circuit for producing the tripping action and being operable when in closed circuit for producing the resetting action.

27. In combination with a roadside divided

into blocks, vehicle carried mechanism, a vehicle carried energizing inductor associated with and adapted to be influenced for tripping the said vehicle carried mechanism, a 5 vehicle carried A. C. source of energy therefore, a second vehicle carried inductor associated with and adapted to be influenced for resetting the vehicle carried mechanism, and a roadside inductor means for each block 10 comprising a pair of inductors in such block connected in circuit, one of the inductors co-operating with the vehicle carried energizing inductor and the other of the inductors co-operating with the second vehicle carried 15 inductor, the said pair of inductors being operable on open circuit for producing the tripping action and being operable when in closed circuit for producing the resetting action, a third inductor in such block arranged 20 at braking distance from said pair of inductors, and roadside means for operating all said roadside inductors of the block in unison.

28. Roadside apparatus for an induction 25 train control system comprising an inductor, a circuit therefor which when closed at a control point produces one operating condition in the inductor and which when open at such control point produces another operating 30 condition therein, and means for detecting a break in said circuit other than at said control point whether or not said circuit is open or closed at the control point.

29. Roadside apparatus for an induction 35 train control system comprising an inductor, an A. C. circuit therefor which when closed at a control point produces one operating condition in the inductor and which when open at such control point produces another 40 operating condition therein, and means including a D. C. circuit for said inductor for detecting a break in said circuit other than at said control point whether or not said circuit is open or closed at the control point.

45 30. Roadside apparatus for an induction train control system comprising an inductor, a circuit therefor which when closed at a control point produces one operating condition in the inductor and which when open at such control point produces another operating 50 condition therein, and means connecting said inductor circuit with the roadside signalling means for detecting a break in said circuit in the vicinity of said inductor whether or not said circuit is open or closed at the control point thereof.

55 31. Roadside apparatus for an induction train control system comprising an inductor, a circuit therefor which when closed at a 60 control point produces one operating condition in the inductor and which when open at such control point produces another operating condition therein, a second inductor, and means connecting the inductors for producing a detecting operation in said second

inductor upon the occurrence of a break in said circuit other than at said control point whether or not said circuit is open or closed at the control point.

32. Roadside apparatus for an induction 70 train control system comprising an inductor, a circuit therefor which when closed at a control point produces one operating condition in the inductor and which when open at such control point produces another operating condition therein, a condenser in said circuit, and a partial circuit shunting said condenser and control point, said partial circuit including means for detecting a break in said circuit other than at said control point. 75

33. Roadside apparatus for an induction 80 train control system comprising an inductor, a circuit therefor which when closed at a control point produces one operating condition in the inductor and which when open at such control point produces another operating condition therein, a condenser in said circuit, and a partial circuit shunting said condenser and control point, said partial circuit including a detecting relay and a direct current 85 source of energy.

34. Roadside apparatus for an induction 90 train control system comprising a plurality of blocks, an inductor for each block, a control circuit for each inductor, the said control circuit including a contact adapted to be opened and closed for producing different operating conditions in said inductor, and means connecting a pair of said inductor circuits for indicating in one inductor circuit 95 an undesirable break in another inductor circuit whether or not said another inductor circuit is open or closed at the control point thereof.

35. Roadside apparatus for an induction 100 train control system comprising a plurality of blocks, an inductor for each block, an energyless control circuit for each inductor, the said control circuit including a contact adapted to be opened and closed for producing different operating conditions in said inductor, and means connecting a pair of said inductor circuits for indicating in one inductor circuit 105 an undesirable break in another inductor circuit.

36. Roadside apparatus for an induction 110 train control system comprising a plurality of blocks, an inductor for each block, roadside signalling means for each block, an energyless control circuit for each inductor, the said control circuit including a contact adapted to be opened and closed for producing different operating conditions in said inductor, and means connecting an inductor circuit of one block with the signalling means 115 and inductor circuit of another block for indicating in the latter an undesirable break in the inductor circuit of the first block.

37. Roadside apparatus for an induction 120 train control system comprising a plurality 125

of blocks, an inductor for each block, roadside signalling means for each block, an energyless control circuit for each inductor, the said control circuit including a contact adapted to be opened and closed for producing different operating conditions in said inductor, and means connecting an inductor circuit of one block with the signalling means and inductor circuit of another block for indicating in the latter an undesirable break in the inductor circuit of the first block, said connecting means comprising a partial energy circuit shunting the control point of the inductor, a control relay in the partial circuit and a circuit under the control of said relay.

38. Roadside apparatus for an induction train control system comprising a plurality of blocks, an inductor for each block, a control circuit for each inductor, the said control circuit including a contact adapted to be opened and closed for producing different operating conditions in said inductor, means for breaking said circuit at another point upon displacement of the inductor, and means connecting a pair of said inductor circuits for indicating in one inductor circuit the break in another inductor circuit due to an inductor displacement whether or not said another inductor circuit is open or closed at the control point thereof.

Signed by said ARCHIBALD G. SHAVER at Chicago, in the county of Cook and State of Illinois, this third day of September, A. D. 1926.

ARCHIBALD G. SHAVER.
